WIRE BRUSH ABRADING DEVICE

Wilford A. Anderson, Minneapolis, Minn., assignor to G. H. Tenant Company, Minneapolis, Minn., a corporation of Minnesota

Application March 28, 1941, Serial No. 385,765

2 Claims. (Cl. 15—179)

This invention relates to new and useful improvements in rotary abrading devices and more particularly to cylindrical wire brushes.

Cylindrical wire brushes have heretofore been used in floor refinishing machines in the operation of refinishing floors and other surfaces requiring such treatment. Such brushes, however, have not proven satisfactory for certain classes of work because of the tendency of the wire bristles thereof accumulating foreign matter which may destroy the efficiency of the brush. This is particularly true when operating on industrial floors which may have deposits of glue, grease, heavy lubricating oils and steel chips, which material may be extremely difficult to remove with an ordinary brush.

An important feature of the invention therefore, is to provide a rotary abrading device or steel brush which is highly efficient in operation, and which is not likely to accumulate foreign matter encountered thereby, when operating on a floor, whereby the operation of refinishing a floor may be greatly expedited and better results obtained.

A further object of the present invention is to provide a rotary wire brush composed of a plurality of disk-like brush elements or sections secured together in spaced relation upon a suitable supporting member and disposed at an angle to the axis of said member, whereby when the brush is operated on a floor, an axial motion is imparted to the bristles thereof in addition to the rotary action of the bristles, whereby a thorough scrubbing and cleaning action is imparted to the floor the entire length of the brush.

A further object is to provide a rotary steel wire brush which is substantially self-cleaning in operation.

A further object is to provide a sectional cylindrical wire brush in which the brush sections are disposed at an angle to the axis of the brush, and means being provided in the construction of the brush for dynamically balancing it, when operated at high speeds, thereby to eliminate vibration.

Other objects of the invention reside in the simple and inexpensive construction of the entire brush assembly, which comprises a plurality of disk-like brush sections spaced apart by annular spacing elements upon a suitable supporting member or core having means at its ends for securing the brush sections and spacers in position thereon; in the provision of a rotary wire brush which may be efficiently operated on substantially all types of floors; in the provision of

such a brush which, when the bristles thereof become worn, may be reversed upon its driving member, whereby new and sharper cutting surfaces may be presented to the floor as a result of the beveled ends of the tufts of steel wires constituting the disk-like brush sections; and, in the provision of a wire brush of the character disclosed, which is extremely practical for heavy duty work and highly efficient in operation.

10 Other objects of the invention will appear from the following description and accompanying drawing and will be pointed out in the annexed claims.

In the accompanying drawing there has been disclosed a structure designed to carry out the various objects of the invention, but it is to be understood that the invention is not confined to the exact features shown as various changes may be made within the scope of the claims which follow.

In the drawing:

Figure 1 is a side elevational view of my improved brush, partially broken away to more clearly illustrate the construction thereof;

25 Figure 2 is a perspective view of one of the brush sections only;

Figure 3 is a view showing one of the spacers for spacing apart the brush sections;

30 Figure 4 is a view showing the weights provided at the ends of the assembled brush for dynamically balancing the brush, when in operation; and

Figure 5 is a detail sectional view on the line 5—5 of Figure 1.

35 The novel rotary brush herein disclosed, is shown comprising a supporting member or sleeve 2, which is cylindrical in cross section and preferably formed of sheet metal.

40 The completed brush, as shown in Figure 1, is composed of a plurality of disk-like brush sections, generally designated by the numeral 3, each comprising tufts 4 of steel wire, suitably secured in an annular supporting element 5, which, as here shown, is made of two sections, suitably

45 secured together. The specific construction of the wire supporting element 5 and the means for securing the tufts of wire bristles 4 therein, forms no part of the present invention, and it is therefore thought unnecessary to show the particular manner of securing the tufts thereto.

50 An important feature of the present invention resides in the unique mounting of the brush sections 3 on the supporting member or sleeve 2, whereby the brush sections are disposed at an angle to the axis a—a of the completed brush,

as illustrated in Figure 1. The disk-like brush sections 3 are spaced apart on the supporting member or sleeve 2 by suitable spacers 6, shown in Figures 1 and 3. The angular mounting of the brush sections on the sleeve 2 is such that the periphery of each brush section 3 will engage the floor with an axial movement as well as a rotary movement, as shown at *b* at the right end of Figure 1, when the brush is rotated. The spacing between the brush sections 3-3 and their inclination with respect to the axis *a-a*, is also such that upon each revolution of the assembled brush, the surfaces of the floor engaged by the peripheries of the adjacent brush sections will overlap, as shown at *c*, whereby it will be noted that a complete and thorough scrubbing or abrading action may be imparted to the floor the entire length of the completed brush, when the brush is rapidly rotated in the operation of the machine.

Because of the brush sections 3-3 being disposed at an angle with respect to the axis *a-a*, means must be provided for dynamically balancing the brush to prevent vibration, when operating at high speeds. The means provided for thus dynamically balancing the brush, is best shown in Figures 1 and 4, and comprises annular wedge-like weight members 7 and 8, one provided at each end of the completed brush in diametrically opposed relation, as shown in Figure 1. To secure the brush sections 3-3, spacers 6, and weight members 7 and 8 in position upon the supporting member or sleeve 2, suitable flanges 9 may be formed at the ends of the sleeve member 2 by outwardly spinning the sheet metal, as clearly shown in Figure 1, whereby the parts 3, 6, and 7 are secured thereto in fixed relation. A suitable key 10, preferably spot welded to the supporting member 2, is received in keyways 11 provided in the parts 3, 6, and 7 to prevent relative rotation of said parts on the member 2. By thus keying the parts to the supporting member 2, they are non-rotatably secured thereto, whereby the sleeve may be rotated in either direction, as when reversing the brush on the driving member of the machine. The spacers 6 are preferably made of aluminum to eliminate weight as much as possible, and the weight members 7 and 8 are preferably made of a relatively heavier metal, such as brass, which I have found suitable for dynamically balancing the brush.

The spacing of the brush sections on the sleeve member 2 and the angle at which they are disposed with respect to the axis *a-a*, may be varied without departing from the scope of the invention, but it is to be understood that the sections 3-3 are so arranged on the supporting core 2 that the portions of the floor engaged by each brush section will overlap, as shown at *b* and *c*, to prevent the formation of streaks or grooves in the floor, when the brush is operated thereon.

The simple and inexpensive construction of the brush, as a whole, is also important in that it greatly reduces the cost of manufacture. When the bristles of the brush sections 3-3 become worn, the brush may be quickly restored to its original condition by removing the brush sections 3-3, spacers 6, and counterbalancing members 7 and 8 from the supporting core 2, and assembling the spacers and weights upon a new core with a new set of brush sections. In other

words, the brush sections 3-3, when they become worn to a certain extent, may be discarded, but the spacing elements and balancing members may be used indefinitely, as will readily be understood. In some instances, it may also be found desirable to substitute for the flanges 9, other means for securing the parts of the brush in position on the supporting sleeve, whereby said parts may be removed from the sleeve without destroying the core. However, because of the inexpensive construction of the sheet metal core 2, I have found it practical to provide a new core and set of brush sections, each time the bristles 4 become sufficiently worn to require replacement.

By the use of the novel brush herein disclosed, industrial floors which may be considered very difficult to refinish with conventional abrading elements or brushes, because of the accumulation thereon of foreign matter, which may be more or less sticky and hard to remove, such as steel chips, glue, grease, and heavy lubricating oil, may be quickly and efficiently refinished without loss of time, because of the self-cleaning action of the brush. This self-cleaning action results because of the axial spacing and angular position of the brush sections 3 on the supporting member or sleeve 2, whereby foreign matter tending to adhere to the bristles 3 is quickly thrown off by the gyratory motion of the brush, when in operation.

I have also found, from actual experience, that a machine equipped with a brush constructed in accordance with the present invention, requires less horse power to drive the brush, and the machine may also be manually propelled over the floor with less effort, which obviously is highly desirable in apparatus of this general character.

I claim as my invention:

1. A rotary abrading brush comprising a supporting member, a series of disk-like brush sections each composed of a plurality of radially disposed twisted cable-like tufts of relatively stiff wire bristles, means for spacing apart said sections on the support and whereby they are disposed at an angle to the axis of the supporting member, whereby when the abrading roll is in operation, a scrubbing and cleaning action is imparted to the floor or surface being treated, the entire length of the brush, and suitable wedge-shaped annular weights being secured to said support in diametrically opposed relation for dynamically balancing the brush, when operated at high speed.

2. In a rotary abrading device, a tubular supporting member, a plurality of disc-like brush sections mounted on said supporting member in parallel relation, annular spacing members mounted on said supporting member between said brush sections thereby to space them apart lengthwise of the device, all of said brush sections being angularly disposed with respect to the axis of the supporting member whereby when the device is rotated, the bristles of said brush sections will engage the floor or surface being treated with a scrubbing action directed lengthwise of the device, each brush section comprising a plurality of radially disposed tufts of wire, and the wires of each tuft being twisted to simulate a steel cable.

WILFORD A. ANDERSON.
